UNITED STATES PATENT OFFICE.

WILLIAM L. MORRIS, OF CHICAGO, ILLINOIS, ASSIGNOR TO ELECTROIL SYNDICATE, OF CHICAGO, ILLINOIS, AN ASSOCIATION COMPOSED OF C. P. JAEGER, L. M. RUTLEDGE, WILLIAM L. MORRIS, AND WILLIAM K. BOOTH.

OIL AND AIR PUMPING SYSTEM.

Application filed September 18, 1922. Serial No. 588,768.

To all whom it may concern:

Be it known that I, WILLIAM L. MORRIS, a citizen of the United States, residing at Chicago, in the county of Cook and State of Illinois, have invented certain new and useful Improvements in an Oil and Air Pumping System, of which the following is a specification.

This invention relates particularly to a system for pumping liquid fuel to a heating furnace, although it may have a more general application wherever it can be used. Among the principal objects of the invention are: to provide a single pump for pumping both air and liquid; to separate the air and liquid; to control the suction of air and liquid; and in general, to produce a system having the construction and operation herein described.

20 In the accompanying drawing, Fig. 1 shows the general system of pumping oil and air, together with the necessary parts, in accordance with the principles of this invention; Fig. 2 is an enlarged sectional view of the float control suction valve; and Fig. 3 is another view of the packed plunger shown in Fig. 2.

In burning a liquid fuel it is desirable to supply air with the fuel in order properly to support combustion, and instead of employing two or more separate pumping outfits for accomplishing this result, the present invention provides only a single pump in connection with an air-tight separating tank for accomplishing the desired result. This system comprises a separating tank 1, a motor 2, a pump 3, and a float operated suction valve 4. An ordinary oil storage tank 5 is provided at a distance from the separating tank and connected to the separating tank is a burner 7 which feeds a furnace 6.

40 A coupling 8 joins the motor and pump, and extending from the pump is a suction line 9 and a discharge line 10. The discharge line extends into the separating tank 1 through a stuffing box 11 and has holes 12 above the oil line in the tank for discharging air, and an open end 13 for discharging oil below the oil line thereby minimizing agitation in the separator.

45 The suction line 9 is connected to the valve 4, and an oil suction pipe 14 extends from the valve into the supply tank 5 with a strainer 15 at its lower end. An air suction

55 pipe 16 also extends from the valve 4 to a point higher than the supply tank 5 with a suction strainer 17 at its upper end. Within the separator tank is a float 18 pivoted at its end 19 upon lugs 20 projecting downward from the underside of the tank cover 60 plate 21 upon which the motor 2 and pump 3 are mounted. Connecting links 22 are attached to the float adjacent its pivot point and at the other ends to a cross pin 23 for 65 operating the float valve, shown more clearly in Fig. 2. The separator tank may also be provided with try cocks 24 above and below the normal oil level so that it can be determined whether the oil line is between the two levels.

Oil is delivered from the separator 1 to the 70 burner 7 through a pipe line 25 and air through a pipe line 26. A pressure relief valve 27 may be connected to the air line 26 and an oil regulating valve 7^a may be provided in the oil line 25. A pressure gauge 28 75 is usually attached to the top of the separator tank and there is a drain outlet plug 29 at the bottom of the tank.

80 Details of the suction control valve are shown more clearly in Figs. 2 and 3 comprising a body 30 having connections for the oil suction pipe 14, the pump suction 9 and the air suction 16. Within the body 30 is an oil closing valve plunger 31 for which there is an oil valve seat 32 corresponding to the oil 85 valve face 33 with vanes above the seat face to offer resistance and permit a long travel of the valve from minimum to maximum oil flow position. The interior of the lower portion of the valve plunger 31 is hollow and 90 below the valve seat face 31 are ports 34 permitting oil to pass into the center of the plunger. Surrounding the central portion of the plunger is a depending shell 30^a adjacent which is the air inlet 16. At the lower 95 end of the plunger is a valve face 35 and in the body member 30 is a corresponding air valve seat 36 below the air inlet 16.

100 A plunger rod 37 extends upwardly through the plunger 31 and is attached to the upper end thereof and to a packing retainer 38 at the lower end. Packing 39 surrounds the retainer for a portion of its length with a spring 40 pressing a washer 41 against the packing to keep it expanded 105 in its portion of the body member. A sleeve 42 surrounding the packing retainer 38 and held in place by the cross pin 33 provides a

fixed abutment for the packing 39 against which the spring 40 may press it. Slots 43 are provided at the lower end of the member 38 and the sleeve 42 for receiving the upper 5 ends of the links 22, as shown more clearly in Fig. 1.

In operation the valve 7^a for controlling the burner is set for a certain amount of opening of the burner 7, the relief valve 27 10 is set for a certain amount of pressure, and the capacity of the pump 3 is fixed and constant; for this condition the suction regulating valve will assume a substantially fixed position and will be without 15 out movement. As the quantity of oil delivered through the pipe connection 25 and the valve 7^a is varied, so also will the oil line in the separator 1 vary, the minimum oil flow causing the float 18 to assume a high 20 position and the maximum flow, the low (but not the lowest) position. The lower face 35 of the plunger approaches the suction air valve seat 36 as the air suction closes, and the oil valve 33 opens. As the 25 air valve closes the air passage being restricted causes a high velocity of air in this valve 4 and creates a greater suction for the oil passing through the center of the plunger 31 thus causing a greater delivery of oil 30 to the separator tank 1. Thus the supply of oil to the separator tank is automatically maintained by the float in connection with the valve 4, and in regular operation oil will be continuously passing through the 35 pump 3 together with the air keeping the pump thoroughly lubricated at all times. The action of the pump produces a pressure in the separator tank 1 sufficient to discharge liquid fuel through the control valve 7^a depending upon the opening thereof, and the admission of air from the pipe 26 being controlled by the same valve. Thus it will be 40

seen that oil and air is pumped into the tank 1 the corresponding amounts being regulated automatically by the float 18, and the valve 4, the air and liquid are separated, pressure is applied to the separator tank, and the oil and liquid are delivered separately and under pressure to the burner 7 in any un-atomized state, the amount of liquid depending 50 upon the opening of the control valve 7^a.

I claim:

1. The combination with a receiver for air and fuel under pressure, of means for utilizing air and fuel therefrom, a pump 55 having a single receiving and discharge line, the latter connected with the receiver, a float in the receiver, fuel and air supply pipes, and a double valve connecting the pipes with the receiving line and controlled by the float for continuously regulating the proportions of fuel and air pumped.

2. In a pumping system of the class described a single pump for both air and liquid, a closed receiver into which the pump 65 discharges, fuel and air supply pipes, a valve for connecting the pipes with a pump including a valve member for oppositely opening the connections to the fuel and air supply pipes, and means depending upon 70 the amount of liquid in the receiver for varying the position of the valve member.

3. The combination with a pump for both air and liquid, of a closed receiver into which the pump discharges, a double valve 75 comprising a slid able member for controlling the admission of air and liquid to the pump, and float controlled means in the receiver for operating the valve by moving the slid able member to vary the amounts of liquids and air admitted to the pump depending upon the amount of liquid in the receiver.

WILLIAM L. MORRIS.
